[57] **CLAIM**

The ornamental design for a toothbrush holder, as shown and described.

DESCRIPTION

FIG. 1 is a perspective view of a first form of a toothbrush holder showing my new design, the broken-line disclosure of a toothbrush being for illustrative purposes only and forming no part of the claimed design;

FIG. 2 is a front elevation view thereof;

FIG. 3 is a left side elevational view thereof, the side opposite being identical in appearance thereof;

FIG. 4 is a top plan view thereof;

FIG. 5 is a rear elevational view thereof;

FIG. 6 is a bottom plan view thereof;

FIG. 7 is a perspective view of a second embodiment thereof; and,

FIG. 8 is a perspective view of a third embodiment thereof.
